UNITED STATES PATENT OFFICE.

ROBERT O. BLAYNEY, OF NIAGARA FALLS, ONTARIO, CANADA.

MOLD FOR TUBULAR CONCRETE STRUCTURES.

1,145,228.

Specification of Letters Patent.

Patented July 6, 1915.

Application filed December 14, 1911. Serial No. 665,741.

To all whom it may concern:

Be it known that I, ROBERT OSCAR BLAYNEY, a subject of the King of Great Britain, resident of the city of Niagara Falls, county 5 of Welland, Province of Ontario, in the Dominion of Canada, have invented certain new and useful Improvements in Molds for Tubular Concrete Structures; and I do hereby declare that the following is a full, clear, 10 and exact description of the same.

The invention relates to improvements in mold forms for tubular concrete structures, as described in the following specification and illustrated in the accompanying drawings 15 that form part of the same.

The invention consists essentially in the novel construction and arrangement of parts, whereby a plurality of separable plate segments are secured together and supported to form a mold.

The objects of the invention are, to facilitate the work of building concrete conduits effecting a saving of time and labor and thereby reducing expense, and to devise a 25 mold formed of a plurality of separable segments which may be taken down and carried through the core without interfering with the advanced portion of the mold, thereby enabling the work to be carried on 30 continuously with a minimum outlay of capital and insuring a thorough bond throughout the entire structure.

In the drawings, Figure 1 is a perspective view of a portion of a mold set up in 35 position. Fig. 2 is an enlarged cross sectional view through one of the wedged joints of the mold showing one of the adjustable supporting legs in part longitudinal section. Fig. 3 is an enlarged elevational face 40 view of one of the center brace connections. Fig. 4 is a diagrammatic plan view of a portion of a conduit mold arranged for a bend. Fig. 5 is a view showing a means of reinforcing a joint. Fig. 6 is a detail view of 45 one of the annular wedges employed in adapting the mold for forming a curved conduit section. Fig. 7 is a detail illustrating the manner of connecting the outer ends of 50 the core supporting arms with the plates of the core.

Like numerals of reference indicate corresponding parts in each figure.

Referring to the drawings, 1 is a base 5 which may be of concrete built in to the trench or other place where the conduit is

to be laid or it may merely represent the ground on which the conduit is to be built.

2 are adjustable leg members, each comprising the threaded rods, 3, tubes 4 and eye rods 5, adapted to rest at their outer ends 60 in the foot members 6 and to be secured at their inner ends to a coupling member 7, the eye ends 5 having suitable bolts extending therethrough and through the bolt holes 8 in said coupling member. The coupling 65 members 7 are formed of a pair of segments adapted to be clamped together around a central tube or rod 9 being held together by the bolts 10 and having the bolt holes 8 arranged in the protuberances 11.

12 is the mold core formed up of a plurality of plates 13, each having their four edges turned inwardly and adapted to fit together to form sections of the desired cross sectional shape which sections are in 70 turn secured together by suitable bolts, the bottom section 14 and the two lower side sections 15 are so formed that longitudinal channels 16 are placed at each side of the center section.

17 and 18 are longitudinal wedge members arranged in pairs and closing the channels 16, being drawn tightly into place by suitable bolts extending through the plate flanges and through suitable holes in said 85 wedges (see Fig. 2). The leg members 2 project through suitable orifices cut in the wedges 17 or 18 and support the rod 9 centrally of the core, the said core being supported upon the adjustable arms 20 formed 90 of a similar construction to the said leg members and secured at their inner ends to the couplings 7 and at their outer ends to the flanges of the plate members as shown in Fig. 7. It will be seen from this de-

scription that the core may be solidly supported a uniform distance from the bed the members 2 being used at frequent intervals but not necessarily at the end of each section. The outer casing 21 of the mold is 100 formed of a plurality of plates 22 having outturned flanged edges adapted to be secured together and suitably supported from the core by suitable separators 23 in the form of short length of pipe surrounding 105 the securing bolts. The lower plates 24 are supported in any suitable manner. An opening 25 is left between the side portions of the outer casing for the placing of the concrete to complete the structure.

In Fig. 4, I show diagrammatically a number of sections of the outer casing of the pipe secured together to form a bend. In order to utilize the ordinary sections used in straight pipes I construct a number of wedge shaped members 27 of annular form adapted to fit between the flanged ends of the casing segments and to be bolted in place. These wedges are formed in segments.

10 Any desired number of the above wedges formed at any desired angle may be used in order to swing the conduit to the required curve.

It will be seen that the pipe may be curved 15 in either direction for any distance desired by the use of such construction, corresponding wedge shaped members being used in the core member. In the diagrammatic plan view of this embodiment of the invention, 20 one of the annular wedge shaped spacing members is shown in section.

In the use of this device, the bed is first prepared and the several segments are secured together in the manner shown and 25 scribed, the longitudinal wedge pieces being preferably arranged to each side of the lower central segment. The adjustable arms are then connected to the collars on the center rod and to the several segments, the leg 30 members 2 being arranged to extend through suitable holes in the wedges. Any desired number of rings thus formed may be secured together to form the core, being supported at suitable intervals by the projecting legs 35 resting upon the foot members in the bed. The lower segments of the outer casing are then placed in position, suitable spacing bolts with pipe collars extending between the casing being used to support the said outer 40 casing and hold it in its relative position in relation to the core. The concrete is then poured into the mold so as to fill around underneath the core and up the sides. The outer casing of the mold is added to from 45 time to time as the filling-in progresses until the last of the concrete completing the structure is placed between the two top plates. When the full amount of concrete is placed in position and becomes sufficiently hard, the 50 mold at the end where the work is started may be taken down from the underside, the legs being disconnected from their connecting collars and drawn inwardly and the longitudinal wedges loosened. The segments 55 are then taken apart and carried through the form and connected up to the farther end of the mold.

In small work say up to six foot diameter I dispense with the leg supports and adjustable arms and reinforce the wedge joints by 60 means of a suitable bridging shown in Fig. 5 in the form of a strap bar 28 secured to

the end flanges of two of the segments and bridging the joint on the inner-side thus giving a perfect rigidity to the whole structure. 65

With the use of a mold such as described the work of construction can be carried on continuously without interruption, as the sections may be taken down one at a time 70 and carried through the succeeding forms so that the work of filling in the concrete need not be interfered with.

What I claim as my invention is:—

1. In a mold for tubular concrete structures, the combination with a plurality of plate segments having inturned radial edge flanges adapted to be temporarily secured together to form a core, of pairs of longitudinal wedge members arranged between the longitudinal flanges of the lower segment and the adjacent segments, bolts extending through the said wedge members and the engaging flanges, threaded rods extending 85 through said wedge members and forming leg supports, tube members threaded on said leg supports, eye rods threaded in the inner ends of the tubes, a coupling member secured to said eye rods, adjustable arms secured to said coupling member and extending radially outward and secured to the inner side 90 of the core, and an outer shell spaced from said core and completing the mold.

2. In a mold for tubular concrete structures, the combination with a core formed of 95 a plurality of plate segments temporarily secured together, of a center rod, coupling members clamped on said center rod, longitudinally adjustable leg members secured to said coupling members and extending outwardly through the wall of the core and forming adjustable supports for said core, adjustable arms secured to said coupling members and extending radially outward and supporting said core, an outer shell 100 spaced from said core and completing the mold, and spacing members arranged between said core and outer shell.

3. In a mold for tubular concrete structures, the combination with a plurality of 110 plate segments having inturned radial edge flanges adapted to be temporarily secured together to form a core, of a bridge member adapted to be secured at the ends to the inner sides of the end flanges of said segments and having an arched central portion adapted to bridge the adjacent longitudinal side flanges of said segments.

Signed at the city of Niagara Falls, this 7th day of December 1911.

ROBERT O. BLAYNEY.
